UNITED STATES PATENT OFFICE.

WILLIS L. RILEY, OF ST. PAUL, MINNESOTA, ASSIGNOR TO LOCOMOTIVE SUPERHEATER COMPANY, A CORPORATION OF DELAWARE.

STEAM-SUPERHEATER.

1,161,976.

Specification of Letters Patent. Patented Nov. 30, 1915.

Application filed December 27, 1909, Serial No. 534,963. Renewed June 28, 1915. Serial No. 36,913.

To all whom it may concern:

Be it known that I, WILLIS L. RILEY, a citizen of the United States, residing at St. Paul, in the county of Ramsey and State 5 of Minnesota, have invented new and useful Improvements in Steam-Superheaters, of which the following is a specification.

My invention relates to improvements in steam superheaters and more particularly 10 although not exclusively is adapted for use in connection with locomotives.

Among the objects of this invention is the introduction of a device of its kind which is less complicated, more efficient, more effective in operation and less liable to disorder than prior devices.

My invention takes the place of a receiver leading from the dry pipe to the steam chest of the cylinders thus occupying less space, 20 leaving the front end of the boiler in the smoke chamber and the boiler tubes clear from obstruction and allowing a good draft on the fire and through said tubes. The main connections lead in a substantially direct line from the dry pipe or boiler to the steam chests and conducts the steam to and from the superheater tubes in the shortest path which is an advantage over previously constructed superheaters. These connections 25 do not increase in size between their ends which is an advantage. The superheater tubes employed in my invention are also arranged so that if they break or leak any one of them can be removed without disturbing the others and a new tube inserted 30 in place of the old one.

In the constructions embodying my invention an important object in view which is attained is to prevent or overcome doubling back in the course of the steam from the time it leaves the boiler until it reaches the steam chests except where it is exposed to the effective action of heat egressing through the boiler flues thus simplifying the construction and accomplishing the desired results in the most efficient and effective manner.

Another important object attained is to provide for expansion and contraction of the parts due to heat and cold and movement of the parts due to excessive strains.

The expense of maintaining and installing my invention is very much less than with prior devices.

55 This application is an improvement on

the construction set forth in my application Serial No. 471,691, filed on the 11th day of January, 1909.

In the accompanying drawings forming part of this specification Figure 1 is a side elevation of a detail of a locomotive illustrating my invention parts thereof being shown in central longitudinal section; Fig. 2 is a front elevation looking into the smoke chamber illustrating my invention; the view 60 being taken of the construction illustrated in Fig. 1; Fig. 3 is a section of the superheater taken upon the line *a—a* of Fig. 1; Fig. 4 is a side elevation of one of the superheaters showing an alternate construction of 65 fastening between the distributor and receiver parts; Fig. 5 is a front elevation of the construction illustrated in Fig. 4; Fig. 6 is a section of Fig. 4 taken upon the line *b—b*; Fig. 7 is a side view of a detail showing the antifriction bearing between the members of the superheater illustrated in Fig. 4; Fig. 8 is a perspective view of one of the antifriction rollers employed in the construction illustrated in Fig. 4; Fig. 9 70 is a side elevation of an alternate construction illustrating the manner of joining the distributor and receiver of the superheater to allow for expansion and contraction; Fig. 95 is a front elevation of the construction 75 illustrated in Fig. 9; Fig. 11 is a side elevation of an alternate construction of my invention; Fig. 12 is a front elevation of the construction illustrated in Fig. 11; Fig. 13 is a detail of the joint between the distributor 80 and receiver illustrated in Figs. 11 and 12 showing another way of allowing for expansion and contraction; Fig. 14 is a side elevation of an alternate construction; Fig. 15 is a front elevation of the construction 85 illustrated in Fig. 14 and Fig. 16 is a section taken on the line *c—c* of Fig. 14.

In the drawings A represents part of a locomotive boiler, B the boiler flues, C the smoke chamber, D the steam chests of the locomotive, F the dry pipe, G the *T* head on the dry pipe in the smoke chamber, H my improved superheater between the *T* head and steam chests and I the superheating steam tubes which are connected with 100 105 and form part of the superheater.

The entire superheater is double in form one superheater J being connected with one branch 2 of the *T* head and one of the steam chests on the corresponding side of the loco- 110

motive and the other K with the opposite branch 3 of the T head and steam chest. These superheaters are similar in construction and incline down in a direct line from 5 the T head to the steam chest with which they connect. The superheater J on one side of the smoke chamber curves out slightly to correspond with the curve in which the ends of the boiler flues B are arranged in 10 the flue sheet. The opposite superheater K is reversed in curvature for the same purpose. These superheaters thus produce a direct conduit without doubling back for saturated steam from the boiler toward the 15 steam chests. As the superheaters are substantially similar in construction it will be understood in the following description that like ordinals refer to similar parts thereof.

Each superheater consists of a distributor 20 4 and a receiver 5 whose initial capacities are the same throughout their lengths and respective lower and upper extremities are closed. The open ends of the distributor and receiver are respectively joined to a branch 25 of the T head and a seat 6 of a steam chest by means of ball joints 7 and 8 which allow for expansion and contraction or movement of the parts without leakage. The distributor and receiver are mechanically joined 30 together transversely by slip joints 9 produced by inter-locking tongues and grooves 10 and 11 integral with said parts, which allow free longitudinal movement between them. (See Fig. 3). In this manner universal movement is permitted between the 35 parts to overcome leakage of steam and permit the parts to be taken apart or adjusted. Arranged in the boiler are a plurality of longitudinal flues B which are larger in 40 diameter than the ordinary flues 12 as many of the flues B being provided as may be desirable for the purpose for which they are intended. In these flues B superheating tubes 1 are carried back and forth, as shown 45 their ends being brought out and connected in multiple with a distributor and receiver. Saturated steam is thus delivered by the distributor to a tube which superheats the steam and delivers it to the receiver. The 50 frames of the distributor and receiver are formed with pockets 13 in the walls of which the ends of the tubes are rolled or beaded to form tight steam joints. Openings 14 containing threaded plugs 15 in the 55 walls of the pockets are arranged opposite or nearly opposite the inner ends of the tubes 1 so that by removing the plugs a cutting tool can be inserted and the ends of the tube cut off. By turning the tube after 60 it has been cut in the manner stated, it can be pulled out clear of the distributor and receiver and the pockets therein and a new tube inserted or an old tube can be repaired without disturbing the superheater 65 distributors and receivers. The portion of

each superheating tube between its ends is formed with a loop 16 which projects in the smoke chamber. The method of securing the ends of the superheating tubes to the casings of the superheater is illustrated in 70 Fig. 3 of the drawings. The shape and form of the distributors and receivers leave the front ends of the tubes in the smoke chamber clear, allow a good draft on the fire and do not reduce draft through the 75 flues of the boiler.

It is desirable to equalize the steam pressure in superheaters and for this purpose I bridge a connection between the lower ends of the receivers 5 by means of the transverse 80 pipe 17 the ends of which are connected in the casings with plugged openings 18 opposite their ends in the same manner as in the construction for fastening the ends of the superheating tubes. In constructing my invention I contemplate various modifications within the scope thereof, a few of which are illustrated by the accompanying drawings.

In Figs. 4 to 7 the joint between the distributor and receiver is produced by a link 90 25 secured by bolts 26 passing through flanges 27 at or near the ends of said parts and journals 28 each of which is produced by an antifriction roller 29 working in guides 30 between the members. By this 95 construction friction is reduced between the members of the superheater and expansion and contraction compensated.

In Figs. 9 and 10 the distributor and receiver overlap side-wise instead of being 100 superimposed as in the preferred construction. These members are joined by bolts 31 passing loosely through transverse passageways 32 and seated at or near their ends upon the casings by conical washers 33 105 which construction allows for expansion, contraction and movement of the parts.

In Figs. 11 to 13 the receivers are connected at their upper ends to equalize pressure of steam which is admitted to the opposite steam chests. A double T head 34 is provided for forming the connection both between the upper ends of the receivers and between the dry pipe F and distributors. The lower end of each distributor is secured 110 to the corresponding receiver by a bolt 35 passing through a slotted opening 36 in lugs 37 which are integral with the casings of the parts 4 and 5. This fastening allows for expansion, contraction and movement 115 between the parts.

In Figs. 14 to 16 the receiver is shown bifurcated, the distributor being held and guided between the bifurcation 38 by an interlocking tongue and groove connection 120 39 which allows for expansion, contraction and movement of the parts.

In accordance with the patent statutes I have described the principles of operation of my invention together with the appara-

tus which I now consider to represent the best embodiment thereof but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. A steam superheater, comprising, in combination with a boiler, boiler flues, smoke chamber and steam chest, a distributor connected with the steam space in the boiler, a receiver connected with said steam chest, said distributor and receiver being connected by an equalizing joint and a plurality of superheating steam tubes connected in multiple with said distributor and receiver and arranged to be heated by heat egressing through the boiler tubes, said parts being so constructed and arranged that steam from the boiler passes in the shortest path to the superheating tubes and from said tubes to the steam chest; whereby a maximum heating exposure is produced upon said tubes with minimum heat loss.

2. A steam superheater, comprising, in combination, with a boiler, boiler flues, smoke chamber and steam chest, a distributor connected with the steam space in the boiler, a receiver connected with said steam chest, said distributor and receiver overlapping each other and joined by an equalizing joint and a plurality of superheating steam tubes connected in multiple with said distributor and receiver and arranged to be heated by heat egressing through said boiler flues.

3. A steam superheater, comprising, in combination, with a boiler, boiler flues, smoke chamber and steam chest, a distributor connected with the steam space in said boiler, a receiver connected with said steam chest, said distributor and receiver overlapping each other and joined together by an equalizing joint in said smoke chamber and forming a substantially straight line of conduit for steam and a plurality of superheating tubes detachably connected in multiple with said distributor and receiver and exposed to the action of heat egressing through said boiler flues.

4. A steam superheater, comprising, in combination with a boiler, boiler flues, smoke chamber and steam chest, a distributor connected with the steam space in said boiler, a receiver connected with said steam chest, said distributor and receiver forming a direct line of conduit for steam and a plurality of superheating tubes connecting in multiple with said distributor and receiver and exposed to the effective action of heat egressing through said boiler flues, said receiver

and distributor being joined together and to said boiler and steam chest by equalizing joints.

5. A steam superheater, comprising, in combination with a boiler, pairs of distributors and receivers having superheating elements associated therewith and adapted to be exposed to the action of heat egressing through the flues of the boiler and an equalizing steam connection between said receivers.

6. A steam superheater, comprising, in combination with a boiler, pairs of distributors and receivers having superheating elements associated therewith and exposed to the action of heat passing through the boiler flues, said distributors being connected with the steam space in said boiler, the distributor and receiver of each of said pairs being movably connected together and an equalizing steam connection bridged between said receivers.

7. A steam superheater, comprising, in combination with a boiler and its flues, smoke chamber and a steam chest, a pair of distributors connected with the steam space in said boiler, a receiver element movably associated with said distributors and superheating elements associated with said parts and exposed to the action of the heat egressing through said boiler flues.

8. A steam superheater, comprising, in combination with a boiler, boiler flues, smoke chamber and steam chests, a distributor connected with the steam space in said boiler, a plurality of receivers associated with said distributor and connected with said steam chests, superheating elements associated with said parts and adapted to be exposed to the action of heat egressing through said boiler flues and an equalizing steam connection between said receivers.

9. A steam superheater, comprising, in combination with a boiler, boiler flues, smoke chamber and steam chests, a distributor connected with the steam space in said boiler, a receiver connected with said steam chests, superheating elements associated with said parts and adapted to be exposed to the effective action of heat egressing through said boiler flues, said distributor and receiver being independently supported.

10. In a superheater for a steam boiler, a distributor adapted to receive live steam from the boiler, a receiver movably associated with said distributor and adapted to allow for longitudinal expansion and contraction of said associated parts and a plurality of superheating elements associated with said distributor and receiver and adapted to be exposed to the action of heat.

11. A superheater for steam boilers comprising a header consisting of a pair of independent header sections vertically arranged, one in front of the other, one of said sections

having means for connection with a steam supply and provided with a saturated steam chamber, the other of said sections having means for connection with the cylinder and provided with a superheated steam chamber, superheater tubes having their ends connected respectively with said saturated steam chamber and with said superheated steam chamber, and slip-joint connections between

said sections to compensate for their relative expansion and contraction.

In testimony whereof, I have signed my name to this specification, in the presence of two subscribing witnesses.

WILLIS L. RILEY.
